UNITED STATES PATENT OFFICE

163,447

SWITCH PANEL

Edwin Drewitz, Long Island City, N. Y., assignor
to Metropolitan Electric Mfg. Co., Long Island
City, N. Y.

Application October 5, 1949, Serial No. 5,305

Term of patent 14 years

(Cl. D26—5)

To all whom it may concern:

Be it known that I, Edwin Drewitz, a citizen of the United States of America and a resident of Long Island City, in the county of Queens and State of New York, have invented a new, original, and ornamental Design for a Switch Panel, of which the following is a specification, reference being had to the accompanying drawings forming part thereof.

Fig. 1 is a front elevational view of a panel showing my new design.

Fig. 2 is a side elevational view of the same as indicated by the line 2—2 in Fig. 1.

Fig. 3 is a top plan of the same, as indicated by line 3—3 in Fig. 1.

Fig. 4 is a bottom plan of the same, as indicated by line 4—4 of Fig. 1.

The dominant feature of the design is shown in full lines in the drawing.

I claim:

The ornamental design for a switch panel as shown and described.

EDWIN DREWITZ.
